ATTYS

UNITED STATES PATENT OFFICE.

HERBERT ELLIOT SINGLETON, OF MELBOURNE, VICTORIA, AUSTRALIA.

BENCH VISE.

Application filed September 19, 1922. Serial No. 589,101.

To all whom it may concern:

Be it known that I, HERBERT ELLIOT SINGLETON, a subject of the King of Great Britain, and resident of 231 Elizabeth 5 Street, Melbourne, in the county of Bourke, State of Victoria, Commonwealth of Australia, importer, have invented certain new and useful Improvements in Bench Vises, of which the following is a full, clear, and 10 exact specification.

My object is to provide an inexpensive construction of bench vise for the purpose of clamping either parallel, taper, or irregular shaped metal or wooden pieces of 15 work. I will now proceed to describe my invention with reference to the accompanying drawings.

Figure 1 is a side elevation of a bench vise constructed according to the present 20 invention.

Figure 2 is a plan thereof, Figure 3 is a longitudinal section of the base plate of the vise, shewing the engagement therewith of the adjustable rear jaw when positioned for 25 gripping the work.

Figure 4 is a transverse section of the base plate taken on the line *a, b*, Figure 3.

Figure 5 represents an inverted plan of the adjustable rear jaw; whilst Figure 6 is 30 a plan of the slidable front jaw of the vise.

Figure 7 is a central longitudinal section of Figure 6 taken on the line *c* (*d*).

Figure 8 is a section of the eccentric or cam employed in the operation of the slidable front jaw.

In the several figures like parts are indicated by similar letters of reference.

My improved bench vise consists of a rectangular shaped cast metal base plate 40 (*a*) which can be permanently fastened to a wooden bench or table, by means of screw threaded bolts and nuts, or wood screws inserted through three perforated ears or lugs (*b*), (*c*), and (*d*), projected from the sides 45 and rear end respectively of said base plate. This plate (*a*) is provided with a longitudinal parallel slot (*e*) to allow of the sliding of the adjustable rear jaw (*f*) to any position on the two parallel toothed racks 50 (*g*) and (*h*), provided in the base plate and situated one at either side of said slot (*e*), according to the width of the work to be clamped.

The adjustable rear jaw (*f*) is retained in 55 the desired position, whilst holding the piece

of work, by means of two projected transverse teeth (*i*) and (*i'*) depending from the rear jaw to engage the beforementioned toothed racks (*g*) and (*h*). The jaw (*f*) is guided and held after adjustment by means of the tongue (*j*) projected from its lower side, and is also held by a T shaped end or cross bar (*k*) adapted to engage the seat (*l*) of a longitudinal recess (*m*) situated in the underpart of the base plate. 60

The adjustable rear jaw (*f*) is provided with a ribbed face plate (*n*) from the underside of which a lug (*o*) is downwardly projected for engaging the slot (*e*), and also for assisting in guiding said jaw during 70 its adjustment on the toothed racks (*g*) and (*h*).

The slidable front jaw (*p*) is positioned upon the base plate, and is adjustable to any angle and may be moved either backwardly 75 or forwardly by an eccentric or cam (*q*) integrally cast with an operating handle (*r*).

The eccentric (*q*) is pivotally positioned on the countersunk headed axial pin (*s*) the end of which is screw threaded at (*t*) to fit 80 into a threaded hole (*u*) provided in the base plate (*a*) and wherein it is secured by means of the threaded nut (*v*).

Integrally cast with the slidable front jaw (*p*) and at right angles to the clamping face thereof, is a flat face plate (*w*) provided with an elongated slot (*x*) through which is passed the axial pin (*s*) of the eccentric or cam, so as to permit of the setting of said 90 jaw to a convenient angle for gripping the front side of the work. The length of this slot is about equal to the amount of throw given to the eccentric (*q*).

For assembling the adjustable rear jaw (*f*) in position upon the toothed racks (*g*) and (*h*) the T-shaped end or cross bar (*k*) of the tongue (*j*) is passed downwardly through the apertured end (*y*) of the slot (*e*) along which it is then moved to the required position upon said racks (*g*) and (*h*). 95

A circular flange (*z*) is projected from the upper part of the eccentric (*q*) to give the handle the appearance of occupying a midway position between the two ends of the slidable front jaw (*p*), and moves in and 100 out of the recess (*z'*) of the latter.

In using my bench vise the handle (*r*) is first moved to a position lengthwise with the base plate, as shewn in Figures 1 and 2. The slidable front jaw (*p*) is then pressed 110

back by the operator, to contact with the heel or lower side of the eccentric (q); so that after the adjustment of the jaws (f) and (p) to suit the shape of the front and rear sides of the work, the eccentric (q) is rotated by operating the handle (r) in a left hand direction. By such means the eccentric acts against the jaw at (p') and thereby pushes said jaw inwardly until the work is gripped. When the pressure is thus applied to the jaw (p) the teeth (i) and (i') of the adjustable rear jaw will bear hard against the engaged teeth of the toothed racks (g) and (h), whilst the cross bar (k) simultaneously engages the seat (l).

Having thus described the invention, what is claimed is:—

1. In a bench vise comprising a base plate having side walls, spaced rack bars carried by the said walls and extending inwardly towards each other to form shoulders, an adjustable rear jaw having teeth thereon to engage the racks, and a tongue on the said jaw projecting downwardly between the rack bars and provided with a head to engage the shoulders formed by the rack bars, a lug on the jaw extending between the rack bars to guide the same, a front jaw provided with a recess and having a base portion provided with an elongated slot turnably mounted on

the base plate for horizontal adjustment, a manually operated eccentric provided with a lip engaging the recess carried by the base portion, and securing means passing through said eccentric and elongated slot to permit 35 clamping action of the said jaw when the eccentric is operated.

2. A bench vise comprising a base plate, a rear jaw slidable on the base plate, means between the base plate and the rear jaw 40 whereby to hold the latter in adjusted positions, a front jaw including an upstanding portion and a lateral portion provided with a slot, the upstanding portion of the front jaw having a recess at its upper outer edge, 45 and an eccentric overlying the slot of the lateral portion of the front jaw and a pin extending through the eccentric and the slot of the lateral portion of the front jaw, the eccentric having an overhanging lip to overlie the recess in the upper outer edge of the upstanding part of the front jaw.

In testimony whereof I have signed my name to this specification in the presence of two subscribing witnesses.

HERBERT ELLIOT SINGLETON.
